(57) **CLAIM**

The ornamental design for a golf cart seat cover assemble, as shown and described.

DESCRIPTION

FIG. 1 is a top and front side perspective view of a golf cart seat cover assemble, showing my new design;

FIG. 2 is a top, front and right side perspective view thereof;

FIG. 3 is a top, front and left side perspective view thereof;

FIG. 4 is a top and back side perspective view thereof; and,

FIG. 5 is a back and bottom side perspective view thereof.

The broken lines shown in the FIG. 5 illustrate portions of the golf cart seat cover that form no part of the claimed design.
